(57) **CLAIM**

The ornamental design for a hose nozzle as shown and described.

DESCRIPTION

FIG. 1 is a first top perspective view of a hose nozzle, according to the new design;

FIG. 2 is a second top perspective view of the hose nozzle;

FIG. 3 is a first bottom perspective view of the hose nozzle;

FIG. 4 is a second bottom perspective view of the hose nozzle;

FIG. 5 is a front elevational view of the hose nozzle;

FIG. 6 is a rear elevational view of the hose nozzle;

FIG. 7 is a top plan view of the hose nozzle;

FIG. 8 is a bottom plan view of the hose nozzle;

FIG. 9 is a left side elevational view of the hose nozzle;

FIG. 10 is an enlarged view of region 10 shown in FIG. 9;

FIG. 11 is a right side elevational view of the hose nozzle;

FIG. 12 is an enlarged view of region 12 shown in FIG. 11;

FIG. 13 is a right side elevational view of the hose nozzle in a first alternate position; and,

FIG. 14 is a right side elevational view of the hose nozzle in a second alternate position.

The dot-dot broken lines in the figures are included for the purpose of depicting portions of the hose nozzle that form no part of the claimed design. The dot-dash are included for the purposes of defining boundaries of the claimed design that form no part of the claimed design. The dot-dot-dash broken lines and the associated reference lines are utilized to identify enlarged views and form no part of the claimed design.
